(57) CLAIM

The ornamental design for a shoe, as shown and described.

DESCRIPTION

FIG. 1 is a bottom view of a shoe showing my new design; FIG. 2 is a bottom front perspective view thereof; and, FIG. 3 is a bottom rear perspective view thereof.

The five broken line circles within the shaded area form no part of the claimed design. The broken lines depicting the remainder of the shoe form no part of the claimed design.
